UNITED STATES PATENT OFFICE.

SIMON COOPER, OF BROOKLYN, NEW YORK, ASSIGNOR TO PINE HILL CRYSTAL SPRING WATER COMPANY, OF NEW YORK, N. Y., A CORPORATION OF NEW JERSEY.

METHOD OF DISPENSING LIQUIDS.

1,283,071.

Specification of Letters Patent.

Patented Oct. 29, 1918.

Original application filed February 11, 1916, Serial No. 77,551. Divided and this application filed October 24, 1917. Serial No. 198,205.

To all whom it may concern:

Be it known that I, SIMON COOPER, a citizen of the United States, residing at Brooklyn, in the county of Kings and State of New York, have invented certain new and useful Improvements in Methods of Dispensing Liquids, of which the following is a specification.

This invention relates to a method of dispensing liquids, and the invention is particularly applicable for dispensing beverages from large inverted containers. The apparatus in operation produces a hydrostatic balance between the column of liquid within the receptacle and the column outside. The liquid is dispensed from the outer column and this disturbs the equilibrium of the columns and tends to produce a flow from the inner column to the outer one. In order to facilitate this flow it is necessary to admit air to the partial vacuum chamber within the container above the column of liquid within it.

One of the objects of this invention is to provide a very simple and efficient method for effecting this admission of air but with the parts so organized as to prevent any flow of water through the air inlet means. Among the other objects of the invention is to provide for enabling the admitted air to be purified if desired.

Further objects of the invention will appear hereinafter.

The invention consists in the general combination of parts, and features described in the following specification while the broad scope of the invention is set forth in the claims.

In the drawings, Figure 1 is a vertical section through apparatus to be used in the practice of my invention; Fig. 2 is a vertical section upon a large scale showing in detail one embodiment of the air inlet means; Fig. 3 is a horizontal cross section on the line 3—3 of Fig. 2; Fig. 4 is a view similar to Fig. 2 but showing a modification; Fig. 5 is a similar view showing another modification; Fig. 6 is a horizontal section on the line 6—6 of Fig. 5; Fig. 7 is another vertical section showing another modification; and Fig. 8 is a cross section on the line 8—8 of Fig. 7.

The container 1 is, for example, in the form of a large bottle received in an in-

verted position in a bottle holder 2. At 55 its lower side or neck 3 it communicates with a delivery chamber or cup 4 and when the container is in position there is developed a hydrostatic balance or state of equilibrium between the liquid column 5 within 60 the container, and the column 6 in the delivery cup or chamber 4, the effect being to produce a partial vacuum in the air chamber 7 above the liquid column 5. Equilibrium is established when the atmospheric pressure 65 and the column 6 equal the water column 5 and the attenuated pressure in the vacuum chamber 7. The communication between the water columns is best effected by means of a duct preferably having an enlarged upper 70 portion 8^a and a reduced lower portion 8^b, the latter extending down into the delivery chamber 4 and below the level of the liquid column 6.

Means such as the stop-cock 9 is provided 75 for drawing off liquid from time to time from the column 6. When this is done the level of the water column 6 descends and this disturbs the equilibrium and produces a flow of liquid from the column 5 to the column 6. When this occurs air should be admitted to the partial vacuum chamber 7, and this means should operate without permitting any outward passage of the liquid. I construct it entirely without valves and in 85 the simplest manner possible. For this purpose, preferably adjacent the junction point of the two portions 8^a and 8^b of the duct I prefer to provide air-inlet means comprising preferably a plurality of small vents 10 90 which may be found in a collar 11 indicated at this point. When the liquid flows down in the duct there is developed a relatively high central velocity in the duct which tends to produce a reduction in pressure near the 95 wall of the upper portion of the duct. At all events an inflow of air occurs at the inlets and this air passes up through the liquid column 5 to the space 7. On account of the small size of these vents and their relatively 100 large number, their combined effect is to give a relatively steady or regular inflow of air, which tends to produce a steady flowing stream at the stop-cock 9 characterized by the absence of violence and splashing. In 105 Fig. 3 by way of example I have illustrated six of these air inlets, but there may be more or less of them as desired. In Fig. 2 the

collar is relatively thick giving relatively long vents and giving relatively sluggish flow through the duct 8^a, 8^b.

By altering the features of construction 5 of the inlet vents the action of the stream flowing through the duct may be varied as desired, for example, by employing a relatively thin collar (see Fig. 4), or by providing such a collar 13 (see Fig. 8) with a relatively great number of vents 14.

The vents may be formed in any manner desired, for example, by drilling the collars or forming the collars of fine gauze, or if desired the vents may be formed by forming them in the inner edge of the collar 15 (see Fig. 6) in which case they may be in the form of small slits 16.

The communicating duct is preferably formed in a plug comprising an upper metal tube 17, the bore of which forms the duct 8^a, and a smaller tube 18 connected by the collar 11, the upper tube having a tapered gasket or bushing 19 of cork, rubber or similar material adapted to form an effective 25 stopper for the bottle neck.

In order to prevent any spilled liquid from finding its way into the delivery chamber I prefer to provide the same with a tight cover 20 surmounted by a funnel-mouthed 30 cup 21 which assists in guiding the bottle neck into place, and provided with drain openings 22. If desired fastening devices such as rivets 23 through the collar may secure these parts all together.

Communication of the chamber 4 with the atmosphere may be maintained by means of a tube 24 which may be provided with a goose-neck 25 which may be provided if desired with a porous disinfectant such as 40 medicated gauze.

As is usual with such apparatus the delivery chamber 4 and contiguous parts of the apparatus are held in a case 26 which 45 may be provided with a removable ice holder 27, access being had to the interior by means of a removable cover 28.

The character of the vents has considerable influence on the variations of level that 50 will occur in the liquid column 6 but in every case the duct 8^b should be long enough to insure that its lower end will never be uncovered (see Figs. 4, 5 and 7). If that 55 should occur it would break the hydrostatic seal which is formed at this point and the apparatus would then not operate in its normal way. It is desirable that the vents should be small, that is, of a capillary na-

ture, because then the surface tension of the liquid standing in the vents is high and operates so that the surface pressure on the outer side of each vent prevents the liquid from flowing out through it.

My invention evidently includes a novel method of dispensing liquids from this kind 60 of receptacle according to which the admission of the air occurs through a constantly open air inlet below the level of the inner columns, without leakage of liquid at any time past the air inlet point; and this air, of course passes up to the Torricellian vacuum 65 chamber. My method of admitting air adjacent the duct between the columns is also advantageous as the outward flow of the liquid in the duct tends to produce a local 70 reduction in pressure that tends to induce 75 an inward flow of air.

It is understood that the embodiment of the invention set forth herein is only one of the many embodiments the invention may take, and I do not wish to be limited in the practice of my invention nor in my claims to the particular embodiment set forth.

The present application is a division of my co-pending application Serial No. 77,551 85 filed February 11th, 1916, for liquid-dispensing apparatus.

I claim:

1. The method of dispensing liquids which consists in holding an inner column of liquid beneath a partial vacuum, holding an outer column of the liquid in communication with said first column and coöperating therewith to form a hydrostatic balance, drawing off liquid from said outer column and thereby disturbing the equilibrium of said columns to cause a flow of liquid from said inner column to said outer column, and maintaining a constantly open capillary air inlet 90 below the level of the liquid in the inner column.

2. The method of dispensing a liquid which consists in holding an inner column of liquid beneath a partial vacuum chamber, holding an outer column of the liquid, maintaining a communicating duct between said columns so that said columns hydrostatically balance each other, drawing off liquid from the outer column and thereby disturbing the equilibrium of said columns, and maintaining constantly open small air inlet vents around the duct through which the liquid will not pass.

In testimony whereof I affix my signature.
SIMON COOPER.
